COMBINED TIMER AND REGULATOR FOR FLUIDS

John D. Beinert, Babylon, N.Y., assignor to International
Patent Research Corp., New York, N.Y., a corporation
of New York

Filed Sept. 20, 1961, Ser. No. 66,776

Term of patent 14 years

(Cl. D52—6)

FIG. 1

FIG. 3

FIG. 2

FIG. 4

FIG. 1 is a side elevational view of the combined timer and regulator for fluids showing my new design;

FIG. 2 is an end elevational view thereof taken from the left hand end of FIG. 1;

FIG. 3 is a top plan view thereof; and

FIG. 4 is a bottom plan view thereof.

The dominant features of my design reside in the portions shown in full lines.

I claim:

The ornamental design for a combined timer and regulator for fluids, as shown and described.
